UNITED STATES PATENT OFFICE.

DAVID FRIEDMAN AND ABRAHAM KIMMEL, OF NEWARK, NEW JERSEY.

DESIGN FOR A DISPLAY DEVICE FOR TIES AND OTHER ARTICLES.

Application filed November 19, 1924. Serial No. 11,405. Term of patent 7 years.

To all whom it may concern:

Be it known that we, DAVID FRIEDMAN and ABRAHAM KIMMEL, citizens of the United States of America, and residents of Newark, in the county of Essex and State of New Jersey, United States of America, have invented a new, original, and ornamental Design for Display Device for Ties and Other Articles, of which the following is a specification, reference being had to the accompanying drawing, forming part thereof.

Figure 1 represents a perspective view of a display device embodying our new design;

Figure 2 represents a horizontal section through the upper portion of the display device.

We claim:

The ornamental design for a display device for ties and other articles, as shown.

DAVID FRIEDMAN.
ABRAHAM KIMMEL.
